UNITED STATES PATENT OFFICE.

ROBERT E. NEWELL, OF IRWIN, PENNSYLVANIA.

AUTOMATIC CUT-OFF FOR GAS-VALVES.

1,388,593.

Specification of Letters Patent. Patented Aug. 23, 1921.

Application filed July 2, 1919. Serial No. 308,196.

To all whom it may concern:

Be it known that I, ROBERT E. NEWELL, a citizen of the United States, and a resident of Irwin, in the county of Westmoreland and State of Pennsylvania, have made a new and useful invention in Automatic Cut-Offs for Gas-Valves, of which the following is a specification.

My invention relates to gas valves and 10 consists of a device which automatically closes the valve opening whenever the flame at the burner, supplied through the valve, is extinguished.

My object is to prevent loss and accidents 15 from the escape of gas through open, unlighted, gas jets whether such escape is due to wind, interruption of the gas pressure, carelessness or other causes.

My invention is illustrated in the accompanying drawings in which Figure 1 is a front elevation of the cut-off mechanism when the valve is closed; Fig. 2 is a similar view when the valve is open and Fig. 3 is in part a side view and in part a vertical longitudinal section through the device when applied to a gas stove or heater and showing the parts when the valve is open and the flame is burning.

The mechanism is included in a housing 30 1. Near the lower part of this housing is a valve chamber 2, supplied by line 3 and opening into a conduit 4 which leads to the stove burner 5.

Two means are utilized for controlling 35 the flow of gas through the valve ports 6: One is a valve plug 7, operated by a handle 8 on the plug stem 9. Plug 7 is provided with a transverse hole 10. Stem 9 is provided with a lateral finger 11. The other 40 control means is a taper bushing 12 which fits inside of valve chamber 2 and surrounds plug 7. Bushing 12 has opposite, transverse holes 13 and 14 adapted to align with ports 6 in the valve and hole 10 in plug 7 to permit the passage of gas, or to be moved out 45 of alignment therewith to shut off the gas.

Integrally secured to the front end of bushing 12 is a large diameter disk 15. At 50 one point in the circumference of disk 15 is an inward projection 16 provided with a notch 17. At suitable points on the disk lugs 18 and 19 are struck up. The former projects outwardly and is adapted to be engaged by finger 11, while lug 19 projects 55 inwardly and is adapted to engage a stop 20 on the face of conduit 4.

On the left hand side of housing 1 is secured one end of a coil spring 21. The opposite end of this spring is attached to disk 15 at a point approximately opposite to projection 16. The tendency of spring 21 is to 60 keep disk 15 and its integral bushing 12 in the position shown in Fig. 1 with holes 13 and 14 out of alignment with valve ports 6.

On the face of disk 15 and near projection 65 16, a pawl 22 is pivoted, having its tail normally held against a pin 23 by a flat spring 24. While I prefer to use this pawl, it may be omitted and its function and the effects of its omission will be explained later. 70

A long flat spring 25 is secured at one end near the top of the housing and at the other end is formed into a catch 26 adapted to engage notch 17 on disk 15.

Spaced from spring 25 is a thermostatic 75 member 27 comprising two or more adjacent strips of thermostatic metal each strip of which is composed of two layers of materials having different coefficients of expansion. Each strip has the side composed of 80 the material with the greatest coefficient of expansion turned away from spring 25. Member 27 is fixed at its upper end and normally passes almost directly in front of the first hole in burner 5. But when it is heated 85 by the flame from this hole, it will bend in an arc which will move its lower end toward disk 15 and that part of the member in the flame of the gas jet will only remain there a very slight period of time before moving 90 to the position indicated by the full lines in Fig. 3. Pivoted on the lower end of member 27 is one end of a hook 28, the opposite end of which passes through a slot 29 in spring 25 and is adapted to engage the lower 95 edge of the slot. If engaged, the movement of pawl 22 from the position in Fig. 1 to its position in Fig. 2, will cause it to disengage the hook from spring 25, while the reverse movement of the pawl will cause the 100 pawl to pivot and to pass hook 28 without difficulty.

Operation: To light burner 5, valve stem 9 is turned to the left, finger 11 engaging lug 18 and thereby moving disk 15 and bushing 12 with it until notch 17 is engaged by catch 26. At this point, holes 10, 13 and 14 are aligned with the openings in the valve chamber 2 and the gas may flow into the burner and be ignited. The alignment of 110 the gas passages will be indicated by the vertical position of the handle 8. By sub-

sequently turning plug 7 to the right, the flow of gas may be regulated as desired.

As the heat from the burning gas affects thermostatic member 27, the lower end of the latter moves hook 28 across spring 25. Gravity will cause the hooked portion to fall and engage the spring when the hook has moved to the position indicated in Fig. 3. The thermostatic member has been operated under the full heat of at least one jet of flame but the effect of that operation has moved the member far enough away from the flame to prevent deterioration of the metal although it still remains within a zone 15 hot enough to maintain it in its distorted position.

If the flame is blown out or the gas pressure is interrupted by any cause, the subsequent cooling of member 27 will cause it 20 to resume its normal position and, in so doing hook 28 will pull catch 26 away from notch 16 and spring 21 will rotate bushing 12 to the position shown in Fig. 1 which will close ports 6 in the valve chamber, and 25 prevent further flow of gas.

As explained above, whenever the operator opens the valve, pawl 22 disengages hook 28 allowing spring 25 to function properly. If it is desired to intentionally 30 extinguish the flame, a slight turn of handle 8 to the right will accomplish the purpose by disalining hole 10 and the resulting cooling of member 27 will cause the latter to operate the hook, catch and spring as previously described just the same as if the flame were 35 extinguished accidentally.

The function of catch 26 is to hold disk 15 and sleeve 12 in open position whenever handle 8 is turned to the open position, and 40 it will do this whether or not the gas is lighted at the burner because pawl 22 disengages hook 28 whenever the pawl passes the hook in an anti-clockwise direction, leaving catch 26 free to function as de- 45 scribed.

If pawl 22 should be omitted from the assembly, spring 25 would always be engaged by hook 28 and catch 26 could only engage notch 17 when the thermostatic member 27 50 was distorted by heat. When lighting the burner, it would therefore be necessary to manually hold handle 8 in the open position for a fraction of a minute until hook 28 and catch 26 moved to the position shown in 55 Fig. 3. While this would be a slight inconvenience, it would, at the same time, be an additional safety measure, as it would prevent, for instance, a child from turning on the gas, then going away and leaving 60 it on. If the valve was opened and the gas remained unlit, spring 21 would close the valve immediately the handle 8 was released.

The device may be manufactured with or 65 without pawl 22 as its function be deemed

desirable or undesirable and without affecting the other elements of my cut-off except as just described.

I claim:—

1. In an automatic cut-off for gas burners, 70 a valve plug and a valve bushing adapted to coöperate to open said valve and adapted to independently close said valve, a member normally holding said bushing in closed position, means adapted to hold said bushing 75 in open position and a thermostatically controlled hook for releasing said means.

2. In a thermostatic gas cut-off; a valve chamber; a valve plug and a valve bushing adapted to coöperate to open the ports of 80 said valve, and adapted to independently close said ports; a catch adapted to hold said bushing when it is so coöperating; a spring, distorted when said catch is so functioning but normally tending to hold said 85 bushing so as to close said ports; and a thermostatic member adapted to engage said catch when heated, and, when cold, to release the hold of said catch on said bushing.

3. In an automatic cut-off for a gas 90 burner, a valve adapted to be opened by a coöperating plug and bushing, and adapted to be closed by said plug or said bushing; means tending to hold said bushing so as to 95 close said valve; a spring catch adapted to hold said bushing when it is turned so as to open said valve; and a thermostatic device operating, when heated, to engage said spring and, when cooled, to move said catch to release said bushing.

4. In an automatic cut-off for a gas burner, a gas supply means normally held in a closed position, a spring element adapted to engage and secure said means when the latter is moved to an open position, a thermostatic strip fixed at a point spaced from said burner and having an unfixed portion adapted to align with an opening in said burner when cool and to move from alignment therewith when hot, and a hook mounted on a moving portion of said strip and adapted to connect with said element when said strip is heated and to disengage same from said means when said strip is cooled.

5. An automatic cut-off for gas burners 115 comprising a valve chamber provided with ports, a bushing adapted to open or to close said ports, a plug adapted to operate said bushing to open said ports and adapted to regulate the passage of gas through said bushing and ports, means normally holding said bushing so as to close said ports, a latch adapted to hold said bushing when the latter is in a position to open said ports, and a thermostatic member adapted, when 120 heated, to engage said latch and, when cooled, to operate said latch to release said bushing.

6. An automatic cut-off for gas burners, comprising a valve, a bushing adapted to 130

be rotated to an open position or to a closed position to permit or to prevent respectively, the passage of gas through said valve, a finger adapted to be manually operated to 5 rotate said bushing to the open position, means holding said bushing in the open position, and a thermostatic member engaging said means when heated, and, when cooled, releasing the hold of said means on said 10 bushing.

7. An automatic cut-off for gas burners comprising a valve chamber provided with ports, a valve bushing and a valve each provided with ports, means for alining or 15 disalining all of said ports, and thermo-

statically operated means for disalining said ports.

8. In an automatic cut-off for a gas burner, a burner supply valve, means automatically holding said valve when the latter is moved to open position, a thermostat adapted to move from contact with the flame fed by said valve when heated thereby and when so moving to engage said means and, when cooled, to render same inoperative. 20 25

In testimony whereof, I have hereunto subscribed my hand this 30th day of June, 1919.

ROBERT E. NEWELL.
